UNITED STATES PATENT OFFICE.

S. T. McDougall, of Brooklyn, New York.

IMPROVED WASHING-MACHINE.

Specification forming part of Letters Patent No. 33,441, dated October 8, 1861.

To all whom it may concern:

Be it known that I, S. T. McDougall, of the city of Brooklyn, county of Kings, and State of New York, have invented certain new and useful Improvements in Washing-Machines; and I do hereby declare that the following is a full, clear, and exact description of the same, reference being had to the annexed drawings, which form part of this specification, in which—

Figure 1 is a side elevation showing part of the mechanism in the interior. Fig. 2 is a back elevation showing the arrangement of the different parts as they appear with the back removed, and Figs. 3 and 4 show the construction of the frames which are used to act on the clothes.

The nature of my invention consists in the employment of one or more pairs of frames or the equivalents thereof arranged in a suitable receptacle for the clothes and water, which frames have a vibrating or reciprocating motion imparted to them by suitable mechanism, so as to cause said frames to act on the clothes to cleanse them, by beating and rubbing, substantially in the manner herein described. My invention also relates to the peculiar construction of the frames aforesaid, as hereinafter set forth.

To enable others skilled in the art to make and use my invention, I will proceed to the description of the construction and operation thereof.

I make use of a tub A as a receptacle for the clothes and water. I erect suitable standards B on the sides thereof, in the top of which are formed proper bearings for a shaft C. Said shaft has several cranks 4 4 2 2. The wrists of 4 4 are grasped by the upper ends of pitmen D, jointed at 7 to rods E, which rods are attached below by pivots 8 to the frames F, and the wrists of 2 2 by the upper ends of pitmen G, their lower ends being connected by accommodating joints to frames H, which latter are hinged or pivoted near the center of the tub. The rods E have suitable guides 3 near the top of the tub, and said rods are so pivoted to the frames F as to permit an oscillation in a plane contrary to that of the vibration of the pitmen when follow-

ing the rotation of the cranks, and in a direction corresponding to that of the vibration of the frames H. (See Fig. 2.) These frames F and H, I usually fill with rows of balls, arranged on rods so as to revolve freely thereon, with one or more slats between, with spaces between the slats, or having grooves in the slats. The frames are seen enlarged in Figs. 3 and 4.

When the machine is to be operated, the clothes are placed in the tub between the frames and under them, and motion being given to the shaft C by the wheel J or otherwise the frames are moved up and down, beating and rubbing the clothes thoroughly and very efficiently.

I usually make one side of the tub inclined, and form ribs or corrugations thereon, to be used for the purposes of a wash-board in cases where the mechanical manipulation does not entirely perfect the cleansing.

The frames H, instead of being two and separate, could be combined in one, and in that case the pivots in the tub might be dispensed with, the guides 3 could be varied, and other modifications of parts will suggest themselves to the expert artisan, and therefore in this invention I do not confine myself to the specific detail of the parts as described, but shall vary them as circumstances may determine, always retaining the same general features, as above set forth.

I claim as my invention and desire to secure by Letters Patent—

1. The employment of the frames F and H, arranged in the tub A and having the reciprocating and vibrating motions imparted to them, respectively, by means of the cranks 2 4 4, through the agency of the pitmen and rods or equivalent mechanism, all arranged and operating substantially in the manner specified.

2. The peculiar construction of the frames, as set forth, with balls and slats alternately arranged therein, substantially as described.

S. T. McDougall.
